UNITED STATES PATENT OFFICE.

ADREN B. STRAWTHER, OF LEXINGTON, KENTUCKY.

CLEANSING COMPOSITION.

No Drawing.

Application filed December 21, 1927. Serial No. 241,730.

My invention relates to a cleansing preparation, particularly adapted for cleaning the hands, and will remove paint, varnishes, duco, printer's ink, shellac, oils, heavy greases, battery acid, et cetera, without injury to the skin, and leaving the same in good condition, without chapping, cracking or other harmful results.

In accordance with the preferred embodiment of my invention, I employ the following ingredients, preferably arranged in the proportions stated:

- 10 300 parts by weight of dry finely divided or powdered wood.
- 15 280 parts by weight of dry powdered sodium carbonate.
- 20 280 parts by weight of dry powdered soap.
- 25 25 parts by weight of dry powdered sodium borate.
- 30 5 parts by weight of dry powdered ammonia (ammonium chloride).
- 35 These several dry powdered ingredients are thoroughly mixed, producing a homogeneous mass, and are then sifted through a wire screen having sixty-four holes to the square inch. This produces a uniformly finely divided or powdered composition, which may be stored in cans or other receptacles for use.
- 40 The finely divided or powdered wood, serves as a harmless but necessary abrasive material or rough surface, which will penetrate the pores and lines of the skin on the hands, carrying with it the other cleansing materials. The finely divided or powdered wood will also absorb the water or moisture which has been previously applied to the hands, thus dissolving the other ingredients of the composition, and at the same time, the material to be removed from the hands is being dissolved. The sodium carbonate is used in conjunction with the powdered soap,

since the powdered soap requires the added sodium carbonate, to remove certain materials from the hands. The sodium carbonate also neutralizes certain acids, et cetera. The ammonia, namely ammonium chloride, is added as it is particularly helpful in dissolving heavy grease and paint, et cetera. The sodium borate functions to soften the water, and also preserve the skin, whereby the preparation is harmless to the skin, although very efficient as a cleanser.

The composition may be placed upon the market in a dry powdered form, as indicated. Some of the powdered composition may be placed upon or in the hands and then water applied to the hands and the usual rubbing or washing operation employed. I also contemplate placing the product upon the market in the form of cakes or tablets, and also in the form of a paste.

It is to be understood that the form of my invention, herewith described, is to be taken as a preferred example of the same and that certain changes may be made in the proportions of the several ingredients and that known chemical equivalents may be employed, without departing from the spirit of my invention, or the scope of the subjoined claim.

Having thus described my invention, I claim:

A hand cleansing composition, consisting of the constituents of substantially 300 parts by weight of finely divided wood, substantially 280 parts by weight of sodium carbonate, substantially 280 parts by weight of soap, substantially 25 parts by weight of sodium borate and substantially 5 parts by weight of powdered ammonium salt.

In testimony whereof I affix my signature.

ADREN B. STRAWTHER.
